US0D1083124S

(12) **United States Design Patent** (10) **Patent No.:** **US D1,083,124 S**
(45) **Date of Patent:** **** Jul. 8, 2025**

(54) **FEEDING BOTTLE**

(71) Applicant: **Beijing Shenchuang Century Information Technology Co., Ltd**, Beijing (CN)

(72) Inventor: **Chengcheng Zhao**, Beijing (CN)

(73) Assignee: **Beijing Shenchuang Century Information Technology Co., Ltd**, Beijing (CN)

(**) Term: **15 Years**

(21) Appl. No.: **35/521,485**

(22) Filed: **Mar. 14, 2024**

(80) **Hague Agreement Data**

Int. Filing Date: **Mar. 14, 2024**

Int. Reg. No.: **DM/237997**

Int. Reg. Date: **Mar. 14, 2024**

Int. Reg. Pub. Date: **Jun. 28, 2024**
